UNITED STATES PATENT OFFICE.

CHARLES BIVORT, OF PARIS, FRANCE.

STENOGRAPHIC OR REPORTING MACHINE.

No. 852,994.

Specification of Letters Patent.

Patented May 7, 1907.

Application filed January 25, 1905. Serial No. 242,664.

To all whom it may concern:

Be it known that I, CHARLES BIVORT, a citizen of the Republic of France, residing in Paris, in said Republic, have invented certain new and useful Improvements in Stenographing-Machines, of which the following is a specification.

This invention relates to typewriters of the class designed to imprint stenographic characters upon a band of paper which is fed longitudinally to the printing mechanism, there being no lateral feed of such paper.

One object of the invention is to provide improved mechanism actuated by the depression of the keys for feeding the paper, feeding the inking-ribbon, and winding up the paper after the same has been written upon.

A further object of the invention is to provide an improved arrangement of the ribbon-spools with regard to the magazine paper-drum and the receiving-drum for the paper.

Other objects of the invention are to provide improved means for changing the direction of the ribbon feed, and to furnish an improved carriage-shifting mechanism.

To these ends the invention consists in a stenographic machine embodying the novel parts and combinations of the same to be hereinafter described and recited in the appended claims.

In the accompanying drawings, in which the same parts are denoted by the same reference characters throughout the different views, Figure 1 is a side elevation, partly in section, of a machine constructed in accordance with the invention, Fig. 2 is a detail plan view of part of the mechanism, Fig. 3 is a bottom plan view of the machine, showing the carriage-shifting mechanism, and Fig. 4 illustrates a device upon which the printed paper band is wound in such a manner that the characters may be read off in their proper sequence.

Referring to the drawings, *a* indicates the base of the machine, and *b* an upwardly-extending support carried by a box *c* screwed to the base at the rear of the same. Said support *b* has journaled at the rear thereof a horizontal magazine paper-cylinder or drum *d*, and at the front, a horizontal receiving drum *e* upon which the paper is to be wound after having been written upon. *f* denotes the platen. The keyboard comprises keys *f*, preferably arranged in two parallel rows, each key being mounted at the forward ex-

tremity of a key-lever *g* pivoted near its rear end to a shaft *h* extending longitudinally to the machine and forming a common pivot for all of the key-levers.

The horizontal rearward prolongation *g'* of each key-lever *g* is operable to lift a horizontal cross-bar *i* which extends across all the key-levers adjacent their upper edges, as shown. Said prolongation or extension *g'* comprises an upwardly-extending arm or lug *g''* the upper end of which enters a rabbet of the type-levers *j* of a carriage *m* located at the rear of the base, the connection between said end and the corresponding type-lever *j* being constant. All of the type-levers *j* are pivoted to a shaft *l* extending longitudinally to the carriage *m* near the upper part thereof, and each such lever carries at its printing end several types or characters. Fig. 1 shows one of the type-levers provided with two types *k*, *k'*; it is obvious, however, that they may carry three or more of such types.

The carriage *m* is shiftable forwardly and rearwardly on the base *a* by means of a device comprising two shift-keys *n*, *n'* arranged at the front of the keyboard. These keys are arranged to act upon levers *o*, *o'* respectively, these two levers being pivoted at *p* to the base *a*, and hidden, for the most part, by the latter. The carriage *m* carries upon its bottom portion depending parallel lugs *r* which extend through an opening *r'* in the base. Between said lugs is secured one end of a connecting rod or bar *q*, the opposite end of which is pivoted to a depending leg of the lever *o*, whereby the depression of the key *n'* effects the rearward shift of the carriage. In the rear of the levers *o*, *o'* is a bar *s*, pivoted intermediately between its ends and having its ends abutting against the corresponding shift-levers. When one shift-key is impressed the other end of the bar *s* is moved against the other key, whereby the latter is raised and the carriage shifted forwardly. It will thus be understood that when the shift-key *n* and lever *o* are depressed, the characters *k* are at the printing point, while if the shift-key *n'* is depressed in order to depress the arm *o'*, the lever *o* rises as a result of the movement of the bar *s*, and in rising the carriage is shifted forwardly through the intermediary of the connecting rod *q*, so that the characters *k'* are situated at the printing point.

The magazine-drum *d* and the receiving-drum *e* are located at the rear and front, re-

spectively, of the machine; they are so arranged as to feed the paper toward the front of the machine. The platen 2 is arranged below said drums and intermediately between the same, its axis being parallel to those of said drums. The ribbon-spools 13 and 14 are in substantially horizontal alinement with the platen 2 and are arranged at the front and rear of said platen, below the paper-drums, and having their axes extending parallel to those of the latter and of the platen, viz., longitudinally to the machine. The ribbon is fed beneath the platen and above the type-levers, as shown in Fig. 1 (in which figure the course of the paper is likewise indicated), the paper and inking-ribbon being fed parallel to each other.

The winding of the paper upon the receiving-drum *e*, the feed of the paper, and the progressive movement of the inking-ribbon, are effected simultaneously when one of the keys is depressed, by mechanism which will now be described.

The upwardly-swinging horizontal bar *i*, which is pivoted at *i'*, and which rises upon the depression of one key or of several together, carries a laterally-extending pin *t* (Figs. 1 and 2) which acts, at each ascent, to lift a lever *u*, pivoted at the rear of the machine, as shown at *u'*, and extending in forward direction. This lever carries at its forward end an upwardly-disposed pawl *v*, which at each oscillation of said lever produces the advance, to the extent of one tooth, of a ratchet-wheel *x*, which transmits this movement, by the intermediary of two pinions *y*, *z*, to a rubber-covered roller 1 bearing against the receiving-drum *e* and imparting to the same its rotary movement, thereby producing the winding of the printed portion of the band of paper upon said drum.

The feed of the paper, which is effected by the step-by-step movement of the platen 2, is effected by a ratchet-wheel 4, fixed to the shaft 12 of said platen, said wheel being engaged by a pawl 5 mounted at the upper end of an arm 3 pivoted at 6 to the base of the machine and actuated by means of a stud 7 upon the lever *u*. The pawl 8, also mounted upon the arm 3, is merely a retaining-pawl.

The feeding movement of the inking-ribbon in either direction is effected by means of a pawl 10 which is mounted directly on the lever *u*, and which actuates a ratchet-wheel 11. To the shaft of said ratchet-wheel 11 is keyed a pinion 16, and said pinion is arranged to transmit movement to either of the ribbon-spools 13, 14, by means of pinions 15, 15' mounted upon a shiftable hanger 15^x on the box *c* and adapted to engage pinions 17, 18, respectively, mounted on the ribbon-spools. These pinions 15, 15' mesh constantly with the pinion 16, but 65 when the hanger 15^x is shifted so that one of

the pinions carried thereby transmits rotary movement to its corresponding pinion 17 or 18 on the ribbon-spool, the corresponding pinion on the hanger is in inoperative position. By shifting the hanger 15^x, either of the ribbon-spools may be actuated from the pinion 16, and the direction of feed of the inking-ribbon may thus be changed as desired. The hanger 15^x is guided on the box *c* by means of a stud-shaft 19^x movable in a slot 19^y in the side-wall of the box *c* and carrying a knob 19^z by means of which the hanger 15^x and its pinions are shifted into the desired position.

The type-levers *j* are returned by leaf-springs 20 bearing against the upper edges of the same, and the parts described as a whole by a single spring 21 acting upon the lever *u* by the intermediary of a link 22. The tension of the spring 21 may be regulated at 85 will by suitable means such as indicated in Fig. 1. The keys and their levers are returned by helical springs 24 depending from the front bar 23 of the machine.

Fig. 4 shows in front elevation the drum and winch device which is also shown in side elevation in Fig. 1. This mechanism is fitted to the bar 23 by means of bifurcated spring lugs 25, and comprises a drum 26 to which a rotary movement may be transmitted by 95 means of a crank 27.

When the speech or discourse is stenographed the band of paper which carries it being wound upon the drum *e*, the said band is cut between the two drums *d*, *e*, and the end thus formed, and which contains matter last written, is arranged upon the drum 26, this drum is rotated, the speech or the record of the same is then wound on the drum 26 in the proper arrangement to be 105 read by unwinding it, or fixed in any convenient manner, removed and filed for the purpose of subsequent reading.

The band of paper unwinding from the drum *d* and passing against the platen 2, is 110 submitted to the tension exerted by a device comprising an arm 28 pivoted loosely upon the spindle of the drum 14; this arm carries, at its extremity, a horizontal rod 29 extending longitudinally of the platen and upon 115 which a roller 30 rotates. This roller bears upon the band of paper in the manner shown in Fig. 1 and tensions the paper solely by the weight of the device.

Having thus described my invention, I 120 claim as new and desire to secure by Letters Patent:

1. In a stenographing machine, the combination of a platen having a ratchet-wheel mounted on the shaft thereof, a paper-feeding drum, a paper-receiving drum, a friction-roller for operating the latter, a ratchet-wheel for actuating said friction-roller, ribbon-spools, a pinion mounted on each of said spoons, type-levers coacting with said platen, 130

key-levers, a lever actuated by all said key-levers, a pawl mounted on said lever and engaging the ratchet-wheel of said friction-roller, an arm carried by said lever, a pawl carried by said arm and engaging the ratchet-wheel on the platen-shaft, a third pawl mounted on said lever, a ratchet-wheel actuated thereby, and means actuated by said last-named ratchet-wheel for rotating either 10 of the ribbon-spool pinions.

2. In a stenographing machine, the combination, with the base, of a carriage mounted on said base and movable in forward and backward direction, a connecting-rod attached to said carriage and extending forwardly beneath the base; a shift-lever pivoted in the front portion of the base and connected with said connecting-rod, a second shift-lever pivoted in the base at the side 15

of said first-named shift-lever but unconnected with said connecting-rod, a bar pivoted to the lower surface of said base and abutting at one edge against said shift-levers, and shift-keys for operating said shift-levers.

3. In a stenographing machine, the combination, with the front bar of the machine, of a paper-receiving device having bifurcated spring-lugs to seat on said bar and comprising a paper-receiving drum and a crank therefor.

In testimony whereof I have signed this specification in the presence of two subscribing witnesses.

CHARLES BIVORT.
